GUARD MECHANISM

Filed Aug. 19, 1931

UNITED STATES PATENT OFFICE

ARLON LITTLEFIELD, OF CRANSTON, RHODE ISLAND, ASSIGNOR TO NEW ENGLAND BUTT COMPANY, OF PROVIDENCE, RHODE ISLAND, A CORPORATION OF RHODE ISLAND

GUARD MECHANISM

Application filed August 19, 1931. Serial No. 558,074.

This invention relates to an improved guard mechanism for machines and the like which is adapted to protect workers and others from injury through contact with rapidly moving machine parts.

One object of the invention is the provision of a device of this character which forms a substantially complete protection from the moving parts of an operating mechanism, which is so constructed as to occupy a minimum amount of space, and in which the parts are so constructed and arranged that access may be had to the machine readily when it is desired to repair or adjust the same.

Another object of the invention is to provide a device of this character comprising a foldable guard member adapted to be supported in position to surround substantially the operating parts of a machine and having a portion capable of being folded back upon itself to give temporary access to the machine, and means for holding the folded and unfolded portions of the guard member in position upon its supports when a portion thereof is folded over to give access to the machine.

Other objects and advantages of the invention relate to various improved details of construction and novel arrangements of the parts as will be more fully set forth in the detailed description to follow.

Referring to the drawings:—

Fig. 1 is a perspective view of the guard mechanism showing the parts in position to enclose substantially completely the operating mechanism of a machine,

Fig. 2 is a vertical transverse sectional view taken through one of the supporting members and through portions of the flexible member carried thereby to illustrate more fully the construction and arrangement of the flexible members and their relation to the supporting members,

Fig. 3 is a detail sectional view transversely of one of the supporting members, substantially along the line 3—3 of Fig. 2, showing the manner of attaching one of the connecting members to the flexible member, and,

Fig. 4 is a front elevational view of certain of the links forming one of the flexible mem-

bers, as they appear in position upon the supporting member.

In the embodiment of the invention illustrated herewith 1 designates either of two oppositely positioned and similarly-shaped supporting members, each of which is preferably curved or bowed to enclose sufficient space for the accommodation of an operating mechanism. The supporting members 1 may be secured to brackets 2 as by means of bolts 3, and the brackets 2 may be secured in turn to the horizontal foundation which supports the machine or to any suitable or desired part of the machine or machine frame.

Each supporting member is preferably of channel shape throughout all or the major portion of its extent and comprises in transverse section an intermediate central portion 4 and upstanding edge portions 5 and 6 forming the channel or seat 7 for the reception of one of the flexible members 8 whereby the flexible members are held against accidental lateral displacement from the supporting member.

The flexible members 8, of which one is associated with each of the supporting members, may be formed from link members 9 so constructed as to be capable of pivotal attachment to each other as by being provided with hook portions 10 engageable with the open portion 11 of the next succeeding link member in such a manner as to permit the necessary degree of pivotal movement of the links relative to each other in rolling up a portion of the protective screen to give access to the machine parts.

Each flexible member 8 is preferably secured to its supporting member at a point adjacent to the end of the flexible member in such a manner as to permit its removal when desired but to hold it in place thereon when in operative position and prevent its accidental displacement from the supporting member. In the present embodiment of the invention a bolt or the like 14 is passed through the open portion 11 of one of the links 9 and removably secured to the intermediate portion 4 of the supporting member by a nut 15 for removably connecting the flex-

ible member to the supporting member. Holding plates 16 and 17 may be carried by the bolt 14 and positioned upon opposite sides of the link member to more firmly hold the 5 parts in position.

A plurality of connecting members 18 extend between the supporting members 1 and connect the oppositely positioned flexible members 8. These connecting members may 10 be formed of metal or any other suitable material and may be of any desired shape throughout the major portion of their extent. In the present instance they are shown as each provided with flattened end portions 19 15 to facilitate their attachment to the links of the flexible members 8. The flattened end portions 19 of each connecting member is secured to oppositely positioned correspondingly located links 9 of the flexible members 20 by means of bolts or the like 20, and a holding plate 21 may be applied to the opposite side of the link member for firmly securing the flattened end 19 of the connecting member to the link.

25 When the supporting members 1 are regularly curved throughout a substantial portion of their extent, engaging members 24 may be secured to the supporting members 1 at intervals for engaging those portions of 30 the flexible members adjacent to the ends of the flexible members which are secured to the supporting members whereby the free ends of the flexible members and the connecting members carried thereby may be rolled or 35 folded over as indicated at 25 to give access to the machine parts without causing the entire protective screen 26 to slide or fall from the supporting members. A form of engaging member 24 which may be employed 40 in connection with the type of flexible members shown herein comprises a sleeve or tube 45 located upon the central portion 4 of each supporting member and held thereon by a bolt or the like 28 passed through the sleeve and the central portion 4 of the supporting member and secured thereto by a nut 29.

The engaging members 24 are so positioned upon each supporting member 1 as to register with and engage the opening in one of 50 the link members when the link members are extended, but without permitting sufficient slack in the flexible member to permit the ready release of a link member from its engaging member accidentally or unless the 55 flexible member is lifted therefrom. The provision of these engaging members temporarily retaining the flexible members in position upon the supporting members permits the operator to fold or roll the free end 60 of the protective screen 26 upwardly upon the supporting members as indicated at 25 whenever he desires to have access to that side of the machine facing the free end of the protective screen and insures that the protective screen will be supported in that po-

sition without falling from the supporting members and without uncovering the other side of the machine. If it is desired to have access to the opposite side of the machine the protective screen may be first rolled up 70 as indicated at 25 and lifted off bodily when the link members will readily free themselves from the engaging members 24. The protective screen may be again placed in position by lifting it bodily to cause the engaging members 24 to engage their link members and then unrolling or unfolding the free end of the screen to cause it to extend over and rest upon the supporting members. The engaging members 24 also serve to retain the 75 protective screen 26 in its extended position upon the supporting members if the protective screen should be subjected to vibrations or struck by any object in such a manner as might otherwise tend to displace it from its 80 position upon the supporting members. 85

What I claim is:—

1. A guard mechanism for machines and the like, comprising oppositely positioned bowed supporting members each of which is 90 provided with a recess formed in the outer face thereof for receiving a flexible member and holding the same against movement laterally out of engagement with said frame member, flexible members each having a portion 95 thereof secured to one of said supporting members and normally extended to lie within the recess in said supporting member, and a plurality of members connecting said flexible members and extending between said supporting members, the free ends of said flexible members together with the adjacent connecting members being foldable upon themselves while sustained by the supporting members to give access to the space enclosed 100 by the guard mechanism.

2. A guard mechanism for machines and the like, comprising oppositely positioned bowed supporting members located within substantially parallel planes and each provided with a substantially continuous seat 110 located upon the outer face thereof for receiving a flexible member, a flexible member having a portion secured to the outer face of each supporting member and adapted when extended to engage the seat formed upon the outer surface thereof, elongated members connecting said flexible members and bridging the space between said supporting members, and holding members carried by said supporting members for engaging portions of said flexible members to hold the flexible members upon the seats formed upon the supporting members and retain the flexible members against movement longitudinally of the 120 supporting members.

3. A guard mechanism for machines and the like comprising oppositely positioned correspondingly shaped supporting members each of which is provided with a substantially 130

continuous external seat for receiving an articulated member provided with open links located at intervals throughout at least a portion of its extent, articulated members carried by said supporting members and engaging said seats, elongated members connecting said articulated members at intervals throughout the major portion of the extent of said articulated members, and engaging means carried by said supporting members and projecting outwardly from the outer faces thereof for engaging certain of the open links in said articulated members and holding the articulated members against sliding movement relative to said supporting members.

4. A guard mechanism for machines and the like comprising oppositely positioned correspondingly shaped supporting members, each of which is provided upon its outer face with a substantially continuous seat of sufficient width to receive and support a flexible member, flexible members carried by said supporting members, and means connecting said flexible members to form a protective screen extending from one supporting member to the other; and means carried by said supporting members for engaging portions of said protective screen to hold the same against accidental removal from said supporting members.

In testimony whereof I have affixed my signature.

ARLON LITTLEFIELD.
